UNITED STATES PATENT OFFICE.

WALTER A. HORNBECK, OF RED BLUFF, CALIFORNIA.

INK DRIER FOR PRINTING PRESSES.

Application filed May 12, 1925. Serial No. 29,786.

The present invention relates to improvements in attachments for printing presses, and has for its principal object to provide a means for drying the ink on the printed sheets immediately after the latter are printed so that they may be stacked immediately without the interposition of blank sheets. At the present time it is customary where hand feed is used to introduce a blotter between each two printed sheets, which blotters have to be removed at a later time at considerable expense for labor. My attachment does away with this method of slip-sheeting, and allows the printed sheets to be stacked immediately.

It is particularly proposed in the present invention to provide a conveyor in operative proximity to the delivery of the printing device so that where the machine is hand-operated the sheets may be placed on this conveyor by the operator, the sheets being automatically removed by the conveyor so as to clear a space for the next sheet.

It is further proposed to provide heating elements in operative proximity to the conveyor for drying purposes, the heating elements being preferably arranged in such a manner that they heat the printed sheets from the top as well as from the bottom. It is further proposed to provide, at the end of the conveyor, a suitable means for stacking the printed sheets, the said means being constructed in such a manner that sliding engagement between any two sheets is avoided, and so that each sheet falls vertically upon the stack of sheets previously formed without rubbing on the said sheet, which might cause the still comparatively fresh ink to blur.

Further objects and advantages of my attachment will appear as the specification proceeds.

The preferred form of my invention is illustrated in the accompanying drawings, in which:

Figure 1 shows a plan view of my attachment as secured to the delivery table of a hand fed printing press;

Figure 2 a front view of the device shown in Figure 1;

Figure 3 an end view of the same;

Figure 4 an end view of a well known type of printing press having my device attached thereto; and

Figure 5 a detail view of a pinion driving a shaft in one direction only.

While I have shown only the preferred form of the invention, I wish to have it understood that various changes or modifications may be made within the scope of the claim hereto attached without departing from the spirit of the invention.

My device consists principally of a conveyor 1, a stacking device 2, and means for heating printed sheets while they are passed on the conveyor to the stacking device.

In Figure 4 is shown the general arrangement of a printing press consisting in its principal features of the bed 3, the platen 4 mounted for operative engagement with the same, the ink fountain 6, the distributing rollers 7 and operating mechanism for the same allowing the rollers to descend from the ink fountain and to slide over the bed containing the type, and a delivery table 8, which in the hand fed type of press is placed in front of the platen within convenient reach of the operator so that the latter may place sheets withdrawn from the platen on the said table. Laterally of the table a wheel 9 is provided which in the general mechanism of the machine operates the distributing rollers, and which for the purposes of my invention is important, in so far as it is in a convenient place to drive my mechanism, to be described hereinafter.

As a supporting structure for my conveyor I provide a rectangular frame 11 adapted to be secured in any suitable manner, as for instance by the screws 12, on top of the delivery table. This frame supports in spaced relation two rollers 13, over which endless belts 14 are passed in spaced relation, the surface of these belts being preferably roughened or provided with bristles 95 so that a sheet of paper placed on the same will readily follow the movement thereof.

Rotary motion is imparted to one of the said rollers by means of the pinion 16 disposed at the end thereof and meshing with a gear wheel 17 placed below the same, which latter is revolved through a bevel gear 18 disposed on a shaft 19 having a pulley 21 secured theron. The latter pulley is connected to the wheel 9 previously referred to by means of the belt 22.

Above the conveyor belts there is supported an electric heating element 23 which

is spaced from the sheet sufficiently far to prevent burning of the same and sufficiently close to be effective as a drying agent. In front of the delivery end of the conveyor there is mounted in the frame a second heating element 24, which latter is disposed below the adjacent roller 13 so that the sheet of paper as it projects forwardly from the delivery end of the conveyor passes over the heating element 24 without coming in contact therewith, whereby the sheet is heated from below for effecting drying of the print thereon. A third roller 26 is provided in advance of the delivery end of the conveyor and in parallel relation to the two rollers 13, the third roller being sufficiently close to the delivery end to cause the advancing sheet to support itself by means of its own stiffness until its front edge reaches the third roller and receives additional support from the same. The third roller receives rotary motion through a belt 27 connecting the pulley 28 fixed to the roller 26 with a pulley 29 formed integral with the pinion 16. The dimensions of the pulleys 28 and 29 are preferably such that the roller 26 revolves somewhat faster than the rollers 13.

From the roller 26 the advancing sheet is delivered on two flat frames 31 disposed at the ends of two parallel shafts or handles 32, which latter are supported in the front member 33 of the frame and in suitable brackets 34. The two frames normally lie in the same horizontal plane, so that a sheet may be delivered on them from the conveyor and from the roller 26, the proportions and distances being such that the sheet substantially reaches from center to center of the frames while the central portion of the sheet is unsupported.

Means are provided in connection with these frames for dropping each sheet separately through the space between the frames. This is done by causing both of the frames to revolve intermittently through half a circle and in opposite directions in such a manner that the two confronting edges of the two frames drop so that the paper supported on the confronting sides of the frame is also dropped, while at the end of the intermittent motion the two frames again lie in a horizontal plane with the former underside on top.

This result is brought about by means of a mechanism operated by the wheel 36 supported on the shaft 37 having its bearing in a transverse member 38, the wheel 36 receiving rotary motion through an idler 39 from the gear wheel 41 at the end of the shaft 19. Reciprocating motion is transmitted from the wheel 36 to two rack bars 42 and 43 mounted for engagement with two pinions 44 arranged on the shafts 32 by means of two links 46 pivoted to two pins

47 and 48 arranged laterally of the wheel 36. To provide against interference of one pin with the other, the construction shown in Figure 1 is selected, from which it appears that the pin 48 rises directly from the face of the wheel 36 near the periphery thereof, while the pin 47 is supported at the end of an arm 49 extending from the pin 48 diametrically across the face of the wheel 36 so that the centers of the two pins lie on the same diameter and are spaced equally from the axis of the wheel 36.

The links 46 engage with the rack 42 through pins 51 which ride in slots 52 in the racks to compensate for the vertical element 80 of the revolving motion of the pins 47 and 48, and the racks themselves ride through slots 53 on pins 54.

It will be noted that revolving motion of the wheel 36 causes the two racks to reciprocate in opposite directions, that is, as viewed in Figure 3, on one-half revolution of the wheel 36, both racks will be drawn inwardly, while on the next half of the revolution both of them will be pushed outwardly. Since for such successful operation of the two frames 31 it is necessary that each be revolved in the same direction instead of being rocked back and forth, it is necessary that the outward stroke of the two racks be rendered inoperative, which can be easily accomplished by causing the pinions 44 to be loose on the shafts 32 and allowing the shafts to be driven one way only by means of pawls 56 on the pinion engaging with ratchet teeth 57 on the shaft, as illustrated in Figure 5.

The operation of the device will be readily understood from the foregoing description. The individual sheets of papers are placed by the operator on the conveyor 1 and are carried individually forward on the conveyor belts, passing first underneath the heater 23 and then above the heater 24 until they reach the roller 26 which advances each sheet further and delivers the same on the two frames 31, which latter are usually made of very light construction. During this process and in timed relation therewith, the two frames are intermittently turned through a one-half revolution so that they drop their sheets successively downwardly to form a stack underneath the two frames.

It will be readily seen that during the whole process if the sheet is placed with the wet print facing upwardly, the print itself does not come in contact with anything throughout the whole operation until the next sheet is placed on top of the same, and in making this contact the second sheet does not rub on the first sheet in any manner, but only lightly drops on the same from the top.

The advantages of my attachment should be understood. Where my attachment is used, there is no necessity for the common practice of slip-sheeting with all its waste in

material and labor, and my drying process is carried out so thoroughly that immediately after one side of the sheet of a certain job is printed the operator may proceed at 5 once with the printing of the other side. My attachment offers particular advantages when used in connection with an automatic feeder, since the rapidity of progress in the latter makes it impossible to use the old 10 method of slip-sheeting. A necessary consequence of this condition thus far was that really first-class paper could not be used in connection with an automatic feeder, since the ink would not dry sufficiently fast. 15 Where my mechanism is used, the device can be made to operate with the same rapidity with which the sheets are delivered from the

press so that the use of my attachment makes possible the use of any grade of paper in connection with an automatic feeder. 20

I claim:

A sheet receiving and delivering device comprising two revolvably mounted parallel shafts having flat supporting elements secured to one end thereof, pinions arranged 25 on the shafts so as to transmit motion thereto in one direction, racks supported for engagement with the pinions, a revolving wheel having diametrically opposed pins projecting therefrom and means connecting the two 30 pins to the two racks for reciprocating the latter in opposite directions.

WALTER A. HORNBECK.
